SACCULATED ARTICLE OF FOOTWEAR

Elijah F. Allen, Los Angeles, Calif.

Application February 19, 1945, Serial No. 578,729

1 Claim. (Cl. 36—11)

My invention relates to a sacculated article of footwear.

More particularly my invention is directed to the art of constructing footwear whereby, for example, a shoe, moccasin, slipper, sandal and similar articles, are formed from a single piece of sheet leather simply by a combination of operations comprising one or more of the steps of splitting, rendering stretchable and shaping.

An important object of my invention is to provide as a new article of manufacture, seamless one piece leather footwear.

Other objects, features and advantages of invention will hereinafter appear.

In the accompanying drawing wherein is shown preferred generic embodiments of the invention expressed in different types of sacculated articles such as footwear.

Fig. 1 is a perspective view of an article of footwear constructed in accordance with the principles of my invention.

Fig. 2 is a plan view of the article shown in Fig. 1.

Fig. 3 is a section taken on line 3—3 of Fig. 2.

Fig. 4 is a perspective view of another article of footwear constructed in accordance with the principles of my invention.

Fig. 5 is an enlarged section taken on line 5—5 of Fig. 4.

Referring in detail to the drawing, Figs. 1 to 3 show a slipper, the portion 7 of the sole which underlies the upper 8 being thinner than the rear portion 9 of the sole because of said upper being upraised therefrom after a splitting operation, presently to be described.

The method of constructing the heel portion 10 of the slipper shown in Figs. 1-3 does not necessarily pertain, per se, to the present invention, and may be formed solely by a shaping and or a stretching and shaping operation as shown.

The slipper shown in Figs. 1, 2 and 3 has a scalloped throat portion 11 at the rear end of its upper 8, said upper being shown much thinner than the underlying sole portion 7. Along each side of the above described upper 8 the sole portion 7 has a marginal extension 12 and also has a marginal extension 13 across its toe portion, these marginal portions of the sole taking the place of the usual upper-protecting selvage or welt.

In constructing the slipper which has been described, a suitable sole-shaped piece is first cut out of a sheet of leather having a proper thickness and then (if the slipper is made by hand) a suitable skinning knife is utilized, first to make a shallow, forwardly arched cut across the upper face of the sole beginning at a point 14 inwardly spaced from one side edge and continuing to a

correspondingly located point spaced a little inward from the opposite side of said sole, the shape of the aforementioned throat 11 depending upon curvature of this cut. Then the workmen will 5 use the knife to cut forwardly from the base of the incision thus made, thereby cutting under the proper thickness, breadth and width of leather required to form the upper 8. The upper-forming portion of the leather will be suitably moistened and will thereupon be stretched and suitably shaped to cause it to conform to the foot of the wearer.

In making certain types of footwear the grain side of the leather will be utilized for the upper, 15 and in other cases the flesh side of the leather will be made use of for the upper all depending on the surface type of footwear desired.

In Figs. 4 and 5 is shown a "scuffing" slipper wherein the heel portion 10 is omitted this type 20 of slipper otherwise being constructed in the manner which has already been described.

It will be seen that if a truly one-piece moccasin or slipper is desired it can be constructed by using a fairly flexible leather and instead of 25 stretching the upper to conform to the contour of the foot, the sole can be shaped to meet the upper above the usual welt line, that is to say, on the side of the foot or last at or near a point where the upper meets the sole in the ordinary 30 Indian style moccasin.

It will also be seen that the starting point for the splitting operation will depend upon the style or type of footwear desired; whether sandal, moccasin, house-slipper, bed-room slipper, street 35 slipper, low shoes, high shoes, or boots or other types of footwear.

For a moccasin, sandal or slipper the splitting can begin at or slightly forward of the ball of the foot, or as far back as the upper is desired.

40 In connection with footwear if an extra sole is desired, the un-cut or un-split margin should be left wide enough to serve as a welt to which the extra sole can be attached by stitching.

It should be understood that the present disclosure is for the purpose of illustration only and that this invention includes all modifications and equivalents which fall within the scope of the 45 subject matter claimed.

What is claimed is:

50 As an article of manufacture, an article of footwear having a sole portion and an upper which are parts of a single piece of leather, the front and side edges of said upper portion being located slightly inwardly from the corresponding edge 55 portions of said sole portion.
